UNITED STATES PATENT OFFICE.

ARTHUR L. ORMAY, OF BROOKLYN, NEW YORK, ASSIGNOR TO HILL PUBLISHING COMPANY, OF NEW YORK, N. Y., A CORPORATION OF NEW YORK.

PROCESS OF PRODUCING ILLUSTRATIONS.

1,179,749.

Specification of Letters Patent. Patented Apr. 18, 1916

Application filed November 2, 1915. Serial No. 59,220.

To all whom it may concern:

Be it known that I, ARTHUR L. ORMAY, a citizen of the United States, and a resident of Brooklyn, Kings county, and State 5 of New York, have invented certain new and useful Improvements in Processes of Producing Illustrations, of which the following is a specification, reference being had to the accompanying drawings, forming 10 a part thereof.

My invention relates to processes of producing illustrations for books, magazines, and the like, and particularly to a method or process which is well adapted to be used 15 in the production of technical illustrations.

In Patent No. 1,143,991 issued June 22, 1915, to the Hill Publishing Company, on an application filed by me April 6, 1915, there are shown and described the various 20 steps of a process of producing illustrations which is termed "back-ground perspective".

According to my present invention, I provide a different process in the same art, which produces what I have termed for 25 convenience, "flat-tone perspective".

One object of my invention is to provide a simple, practicable, and inexpensive process for producing illustrations that show the article, machine, machine element, mechanism, or engineering structure and its surroundings in a particularly striking manner, the illustration being based on an outline perspective and having only two grades 30 of shading,—one solid color, usually black, and the other a pattern shading which, as hereinafter explained, produces a striking contrast both with the white, unshaded areas and with the areas shaded in solid colors.

Other objects and advantages of my invention will be set forth hereinafter, and in order that my invention may be thoroughly understood I will now proceed to describe the same in the following specification and then point out the novel features thereof in 45 appended claims.

Referring to the drawings: Figure 1 is a line drawing which illustrates the first step in my process. A negative produced by photographing the drawing of Fig. 1 is 50 shown in Fig. 2. Fig. 3 is a copper, or other plate or line engraving, produced from the negative of Fig. 2, with the unshaded areas gamboged. Fig. 4 shows the plate of Fig. 3, after it has had a Ben Day film

rolled over it to produce the required pattern on the white areas to be shaded, the gamboge washed off, and the plate baked and etched. Fig. 5 shows an illustration produced from the plate of Fig. 4.

If it is assumed that it is desired to illustrate a part of a machine for a book or technical magazine; for example,—an outline perspective of the desired part is first made similar to that of Fig. 1. A convenient way to produce this is to obtain a photograph of the part to a suitable scale for reduction, then outline on the photographic print, so that they will stand out through a tracing cloth or paper, the parts which would be represented by lines in a line drawing. A tracing is then made from the photograph, thereby producing the desired perspective line drawing of the object.

An alternate method is to ink over the outline on the photograph and then bleach the color from the photograph, leaving the outline in black lines on a white surface. On this drawing the areas which are to be shaded solid are filled in in black and the areas which are to have the pattern shading in the final drawing, may be indicated by filling in with light blue pencil shading to guide the engraver without producing any effect on the negative which is taken of it. Instead of shading the original line drawing, or tracing, with light surface shading, a print of the negative taken thereof, may be made and shaded to constitute a guide for the engraver. Next, a negative is taken of the line drawing. This is as shown in Fig. 2 of 90 the drawings. A positive is then printed from this negative on metal to give the negative cut. This is gamboged or coated with soluble matter, to cover the entire surface of the plate except the areas to be shaded. 95 Next, a Ben Day film is made and is rolled over the plate, covering the areas which are not shaded solid, with the required pattern. The gamboge is then washed off and the plate baked and etched in a well known manner. The plate then appears as shown in Fig. 4 and is ready to be used in the production of printed illustrations which have the appearance of Fig. 5.

The following advantages of the flat-tone perspective illustration of my invention may be mentioned. First, the illustration is particularly clear since all the confusing

intermediate tones of an ordinary half-tone cut between black and white are eliminated. This is particularly advantageous for technical illustrations as compared with the usual half-tones, the original photograph being in many instances taken under very unfavorable lighting conditions. Sufficiently high-grade retouching to overcome these deficiencies is not only prohibitive on account of the expense involved, but would also cause serious delay in the making of engravings. Second, the flat-tone perspective on the other hand may be made at relatively small expense and the cuts are as clear as a line engraving. Third, my process of illustration affords an opportunity to emphasize, in a striking manner, certain details of unimportance or interest. Fourth, the effect of the entire illustration is very striking so that it quickly catches the eye of the reader and holds attention on account of its poster effect. Fifth, from the printing point of view, it is much easier to print the flat-tone perspective than any half-tone, because little or no "make-ready" will be necessary to insure the proper effect, and if any is used it need be of the simplest character.

Various other advantages and detailed variations of my invention will suggest themselves to those skilled in this art, and I intend that only such limitations be imposed as are indicated in the appended claims.

What I claim is:

1. The process of producing plates for pictorial illustrations having shaded areas in 35 solid and other shaded areas in pattern, which consists of making a negative from a line drawing having only a solid shading, printing from said negative on a photo-sensitized metallic plate, gamboging said plate 40 except for the areas to be pattern shaded, treating the part of the plate which is uncoated to produce a pattern shading, and etching the plate.
2. The process of producing plates for 45 pictorial illustrations which consists of making a negative from a line drawing having only solid shading, printing from said negative on a photo-sensitized metallic plate, gamboging said plate except the areas to be 50 pattern shaded, rolling a Ben Day film over the plate and then removing the gamboge and etching the plate.
3. The process of producing pictorial 55 illustrations which consists of making a negative from a line drawing having only solid shading, making a plate therefrom, and adding to said plate on parts thereof of predetermined pattern light surface shading of 60 uniform density.

In witness whereof, I have hereunto set my hand this 30th day of October, 1915.

ARTHUR L. ORMAY.
